UNITED STATES PATENT OFFICE.

GEORGE W. MORSE, OF JERSEY CITY, NEW JERSEY, ASSIGNOR TO CLARION CHEMICAL COMPANY, OF NEW YORK, N. Y., A CORPORATION OF NEW YORK.

DENTIFRICE.

No. 808,105.

Specification of Letters Patent.

Patented Dec. 26, 1905.

Application filed May 18, 1905. Serial No. 261,068.

To all whom it may concern:

Be it known that I, GEORGE W. MORSE, a citizen of the United States, residing at No. 249 Harrison avenue, Jersey City, New Jersey, have invented certain new and useful Improvements in Dentifrices, of which the following is a specification.

My invention relates to a compound dentifrice-powder possessing superior bactericidal, germicidal, detergent, and cleansing properties due to the production of hydrogen peroxid when the compound comes in contact with the secretions of the mouth, said compound further possessing new and superior abrasive properties.

According to my invention I combine with a powdered abrasive substance—such, for instance, as chalk—and with a saponaceous substance, such as powdered white castile-soap, a combination powder barium-hydrogen-orthophosphate and barium dioxid in an exceedingly finely divided and refined condition.

The preferred proportion of the above ingredients is as follows: Of the combination powder barium - hydrogen - orthophosphate and barium dioxid I take about seventeen per cent., and this I combine with seventy-five per cent. of precipitated chalk and eight per cent. of castile-soap. The said combination powder consists of about ninety per cent. of barium-hydrogen-orthophosphate and ten per cent. of barium dioxid. To the final compound may be added a suitable flavoring material ordinarily used in tooth-powders or found to be desirable and any of the other usual and suitable ingredients of tooth-powder.

The above proportions may of course be varied as desired without departing from the spirit of my invention.

When the dentifrice containing the above-mentioned ingredients is placed in the mouth, the acid secretions acting on the combination powder aforesaid produce a certain amount of hydrogen peroxid, which by its well-known

action is extremely efficient in removing tartar and other organic matter from the teeth and preventing deposits thereof. At the same time the said combination powder, by reason of its nature and extremely finely divided and refined condition, acts as a most advantageous polishing and abrasive agent, exceeding in efficiency all polishing and abrasive agents heretofore used.

Altogether this dentifrice is a decided and vast improvement upon all forms of dentifrice now in use or known, exhibiting all the valuable antiseptic and germicidal properties of H_2O_2 without any caustic burning or other harmful effects and, furthermore, exhibiting such polishing and abrasive properties as have never heretofore been known, said properties at the same time causing no injurious or harmful effects.

The dentifrice may be prepared and marketed in powder, tablet, lozenge, or other forms, as may be desirable.

Having thus described my invention, what I claim is—

1. A dentifrice comprising the combination powder barium - hydrogen - orthophosphate and barium dioxid, with a suitable abrasive material, substantially as described.

2. A dentifrice comprising the combination powder barium - hydrogen - orthophosphate and barium dioxid, a suitable abrasive material and a saponaceous material, substantially as described.

3. A dentifrice comprising about seventeen per cent. of the combination powder barium-hydrogen-orthophosphate and barium dioxid, about seventy-five per cent. of precipitated chalk and eight per cent. of castile-soap, substantially as described.

In testimony whereof I affix my signature in presence of two witnesses.

GEORGE W. MORSE.

Witnesses:

HENRY E. COOPER,
WENDELL P. MCKOWN.
